CLAIM

The ornamental design for an indoor intelligent PTZ camera, as shown and described.

DESCRIPTION

FIG. 1 is a bottom and rear perspective view of an indoor intelligent PTZ camera of the present invention;

FIG. 2 is a top, front and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the indoor intelligent PTZ camera that forms no part of the claimed design.
